UNITED STATES PATENT OFFICE.

AMOS S. BLAKE, OF WATERBURY, CONNECTICUT.

IMPROVEMENT IN WEIGHT AND LEVER ATTACHMENTS FOR DOORS AND GATES.

Specification forming part of Letters Patent No. 35,988, dated July 29, 1862.

To all whom it may concern:

Be it known that I, AMOS S. BLAKE, of Waterbury, in the county of New Haven and State of Connecticut, have invented a new and improved weight and lever attachment to be applied to doors, gates, &c., for the purpose of closing the same after being opened; and I do hereby declare that the following is a full, clear, and exact description of the same, reference being had to the accompanying drawings, making a part of this specification, in which—

Figure 1 is a face or side view of my invention applied to a door, the latter being shown in a closed state; Fig. 2, a plan or top view of Fig. 1; Fig. 3, a side view of the invention applied to a door, shown in an open state.

Similar letters of reference indicate corresponding parts in the several figures.

This invention consists in connecting a weight to a bent lever which is attached to the framing of the door or to the post of a gate, and connecting said lever to the door or gate by means of a rod arranged in such a manner that the weight is made to act in the most efficient way in closing the door or gate, and the latter, when thrown fully open, allowed to remain in that position.

To enable those skilled in the art to fully understand and construct my invention, I will proceed to describe it.

A represents a door hung upon hinges, as usual, and B a part of the frame thereof or a part of the partition in which the door is placed.

C is a lever which is of right-angular form and has its upper end, a, bent so as to fit in the door frame or partition B. This upper part of the lever is not fitted directly into the frame or partition, but is fitted loosely in a tube or socket, b, which is firmly secured therein, so that the upper end of the lever forms its center of oscillation, the tube or

socket b being the fulcrum or fulcrum-bearing. The lower or disengaged end of the lever C has a weight, D, attached, and E is a rod, one end of which is bent to form a hook, c, which is fitted loosely in an eye, d, at the angle of lever C. The opposite end of the rod E is bent downward and is fitted loosely in an eye, F, attached to the door A.

The lever C may be constructed of a piece of wire, so bent as to form in one piece the upper part, a, and the eye d, as shown in Fig. 1.

When the door is opened, the rod E will actuate the lever C and raise the weight D, which, when the door is left free, will by its gravity depress the lever and close the door. When, however, the door is thrown fully open, or to such an extent that the thrust or pressure of rod E will be nearly in line or in a plane parallel with the frame or partition B, the door cannot close under the action of the weight D; hence, when it is desired to have the door remain open, all that is required is to throw it fully back.

This invention may be constructed and applied at a small cost. The weight D, for ordinary purposes, need not exceed two and one-half pounds, and the weight of the other parts—to wit, the lever C and rod E—need not exceed two pounds.

The invention has been practically tested and answers admirably well, and is applicable to gates as well as doors.

Having thus described my invention, what I claim as new, and desire to secure by Letters Patent, is—

The combination of the weight D, lever C, and rod E, applied to the door or gate, to operate as and for the purpose set forth.

AMOS S. BLAKE.
